UNITED STATES PATENT OFFICE.

WILLIAM H. McCLELLAND, JR., OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

CIRCUIT-BREAKER.

1,314,883.

Specification of Letters Patent.

Patented Sept. 2, 1919.

Application filed April 16, 1917. Serial No. 162,259.

To all whom it may concern:

Be it known that I, WILLIAM H. McCLELLAND, Jr., a citizen of the United States, residing at Wilkinsburg, in the county of 5 Allegheny and State of Pennsylvania, have invented certain new and useful Improvements in Circuit-Breakers, of which the following is a specification.

My invention relates to circuit breakers 10 and more particularly to thermo circuit breakers.

I will describe one form of circuit breaker and one form of apparatus employing the same, embodying my invention, and will 15 then point out the novel features thereof in claims.

The accompanying drawing is a view showing in elevation one form of circuit breaker embodying my invention, and one 20 form of apparatus employing such circuit breaker and also embodying my invention, the apparatus, however, being shown only diagrammatically.

Referring to the drawing in detail, the 25 circuit breaker, which is designated generally at C, comprises in this embodiment a base plate B and a top plate T, formed of insulating material and supported in spaced relation to the base plate by means of rods 30 R. An L-shaped lever L located between the plates B and T at one end thereof is pivotally mounted for swinging movement upon an ear E formed on the base plate B. The long arm of the lever L is provided 35 with insulating studs S upon which is secured a resilient contact finger F. This contact finger is adapted to coact with a stationary contact G mounted on an angle bar H, such bar being secured to the upper side

40 of the plate T by a binding post P. Interposed between the short arm of the lever L and the base plate B is an expansible spring K, which spring serves to bias the lever L outwardly, that is, toward such position

45 that the contact F—G is open. As shown in the drawing, the contact finger F is held, against the action of the spring K, in engagement with the contact G by means of a latching device generally indicated at D.

50 The latching device D comprises in this instance a latching lever d pivotally connected at one end to a link d', which latter in turn is pivotally mounted on the base plate B. The free end of the lever d is formed with

55 a hook d" for engagement with a keeper d'

secured to the free end of the long arm of the lever L.

A designates a tripping arm for raising latching lever d away from the lever L. This arm is pivoted at one of its ends to a 60 bracket Z secured to and depending from the top plate T. The tripping arm A is biased upwardly by a contractile spring K', the lower end of the spring being connected to the lever adjacent the free end thereof 65 while its upper end is connected to a screw V adjustably mounted in the top plate T. A block Q formed of insulating material is secured to the upper side of the lever A adjacent its free end to engage the latching 70 lever d, such block acting as a spacing means for the levers, as will be understood. Upward movement of the lever A is restricted by means of a thermostat X, which, as here 75 shown, consists of a wire formed of a material having a large co-efficient of expansion, such, for example, as German silver. One end of this wire passes freely through an opening z, formed in the bracket Z, and is secured to a screw V' adjustably mounted 80 in a second bracket Z'. The opposite end of the wire is suitably secured to the outer end of the tripping lever A, as shown, such end, however, extending through a block J, secured to the lever whereby the wire is maintained in spaced relation to the lever A 85 throughout its entire length. The brackets Z and Z' are spaced apart by a block Y formed of insulating material, and are provided with binding posts P² and P³, respectively, arranged upon the upper side of the top plate T, as shown.

By connecting the binding posts P and P² by a conducting wire W, it will be evident from the preceding description that the 95 contact F—G when closed is in electrical communication with the binding post P³ through wire W, post P², arm A, wire X, and bracket Z'.

As shown in the drawing, the circuit 100 breaker C is in set position: that is the latching device D is in engagement with lever L so that the contact finger F is held in closed position. By properly adjusting the tension of the spring K' and of the wire X, through 105 the medium of their respective screws V and V', the forces exerted upon the tripping lever A by such members may be so controlled that when current of a predetermined value or less flows in wire X, or when 110

current of a higher value flow momentarily in this wire, the arm A is maintained in its inactive position. With the circuit breaker in this position, assume that current of 5 greater than the predetermined value flows through wire X for a considerable length of time. This current will heat the wire to such a degree that the expansion of the wire is sufficient to allow arm A to rise and lift 10 latch d away from the keeper d', thus allowing contact F—G to open. Current then ceases to flow through wire X, so that this wire cools off and draws arm A down, allowing contact F—G to again be closed in 15 the operation hereinafter described.

In order to reset the breaker, I provide means which I will now describe. N designates a disk or wheel which is adapted to be rotated by means of a reversible electric 20 motor M. The disk N is operatively connected to the latching device D by a link U, one end of the link being eccentrically mounted upon the disk while its opposite end is pivotally connected to the link d'. 25 Movement of the disk N either clockwise or counter-clockwise is restricted to substantially one cycle by means of a lug N' formed on the periphery of the disk, which is adapted to engage a stop O. From this construction and arrangement, it will be seen that when the motor M is energized to rotate in one 30 direction or the other, rectilinear movement is imparted to the latching lever d through the medium of the disk N, rod U and link d', as will be understood. By virtue of this movement of the latching lever, it will be obvious that when the tripping lever A returns to its normal position due to the cooling of the wire X, as previously described, 35 and the motor M is energized, the latching lever is moved forward to cause the hook d' to engage the keeper d', and then rearward to return the lever L and contact finger F to their normal positions, as shown 40 in the drawing. It is to be noted that before the lever L can be returned to its normal position to close contact F—G it is necessary that the thermostat X, and consequently the lever A, shall have returned to 45 their normal positions, otherwise the latching lever d when moved forwardly would fail to engage the lever L by reason of the fact that the tripping lever retains the latching lever in a position above that in which 50 it can engage keeper d'. 55

I will now describe one form of apparatus employing the circuit breaker C, which apparatus is, as here shown, a railway traffic controlling apparatus. The apparatus comprises a railway switch 12, to which is connected an operating rod 13. A pin 14 is formed on the free end of the rod 13 and is adapted to ride within a cam slot 15 formed in a slide plate 16. An electric motor M' imparts longitudinal movement to the plate 16

through the medium of a gear 17 fixed to the motor shaft 18 and meshing with the toothed edge 19 of the slide plate 16. Such movement of the plate 16 in either direction causes the pin 14 to follow the course defined by 70 the slot 15, and thereby imparts rectilinear movement to the operating rod 13. By this operation switch 12 is shifted from normal position to reverse position or vice versa, according to the direction of movement of 75 the slide plate 16, as will be understood by those versed in the art.

In electrically-operated switch movements of this character a cut-out switch for the motor M' is usually provided to deenergize 80 the motor after the switch has reached either of its extreme positions. The cut-out switch is indicated generally at 100, and as here shown, comprises a bar 20 fixed to one end of the plate 16 for movement therewith, 85 such bar being formed with a longitudinally extending slot 21 of a length less than that of the cam slot 15. A switch blade 22 pivoted at 23 is provided with a pin 24 which rides in the slot 21 so that when the bar 90 20 is moved by the plate 16 blade 22 will be moved to engage either of the contacts 25 or 26 according to the direction of movement of the bar. Owing to the length of the slot 21 and the location of the blade 22, the 95 shifting of the blade from contact to contact does not occur until the slide plate 16 has nearly reached the end of its stroke so that the motor M' may be maintained energized during transit of the switch but will 100 be deenergized after the switch has reached either of its extreme positions.

A source of current such as a battery 27 supplies current to the motor M'. A circuit controller indicated generally at 200, 105 together with the cut-out switch 100, controls the supply as well as the polarity of current from the battery 27 to the motor M' to cause rotation of the motor in one direction or the other, according as the circuit controller and cut-out switch assume one position or the other. The circuit controller 200 comprises a switch blade 28 pivoted at 29 for engagement with either of a pair of contacts 30 and 31. The switch blade 28 is 110 actuated by the motor M through the medium of a gear 32 fixed to the motor shaft and meshing with a rack bar 33, which latter is in turn connected to the switch blade 28, as shown. 115

The motor M is supplied with current from a battery 10, and is controlled by a pole-changer 11 operated by a lever 11a, which lever is usually one of a plurality of similar levers in an "interlocking machine." 125

The circuit breaker C is included in, and controls, the circuit for motor M' in a manner which will appear hereinafter.

The operation of the entire apparatus is as follows: In the drawing, the switch 12 130

is shown in the "normal" position, and the other parts of the apparatus are shown in the positions corresponding to this position of the switch. When it is desired to move 5 the switch 12 to its "reverse" position, pole-changer 11 is manually reversed, whereby current from battery 10 is supplied to motor M in such direction as to cause rotation thereof counter-clockwise. Motor M being 10 energized, gear 32 and disk N are now caused to rotate with the motor. With the rotation of disk N, latching device D is operated to open the contact finger F but immediately closes such contact finger by virtue 15 of the fact that the thermostat X remains in its normal condition. When gear 32 is rotated, rack bar 33 is drawn to the right, thereby shifting the switch blade 28 from contact 31 to contact 30. It will be 20 noted that the gear 32 and the rack bar 33 are so proportioned with respect to the disk N that the operation of latching device D, just described, is completed before switch blade 28 engages contact 30. With the blade 25 28 in this position, current is supplied to the motor M' through the following circuit: from battery 27, through wires 36 and 37, contact 30, blade 28, wire 38, motor M', wire 35, binding post P³, bracket Z', screw V', 30 wire X, tripping lever A, bracket Z, binding post P² wire W, binding post P, contact G, contact finger F, wire 34, blade 22, contact 25, wires 39 and 40 to battery 27. Although current is now traversing the ther- 35 mo-wire X, this wire is so proportioned that the heat generated therein by such current is insufficient to expand the wire to such degree as to cause arm A to release the circuit breaker. Furthermore, although a com- 40 paratively heavy current flows through wire X while the motor M' is starting, the duration of this heavy current is insufficient to cause wire X to expand sufficiently to trip the circuit breaker. As the slide plate 16 45 approaches the end of its stroke, pin 24 abuts the end wall of the slot 21, causing blade 22 to swing and engage contact 26, thereby excluding the battery 27 from the motor circuit to cause deenergization of the 50 motor M'.

To throw the switch 12 from reverse to normal position, pole-changer 11 is moved to the position shown in the drawing, whereby motor M will be energized to rotate clockwise and thereby cause the entire apparatus to operate in the same manner as when moving the switch from normal to reverse position but in a reverse direction. By the reversal of the blade 28 during this reverse

movement of the apparatus, motor M' is then 60 energized through the following circuit: from battery 27, wires 40 and 41, contact 31, blade 28, wire 38, motor M', wire 35, etc. to blade 22, contact 26, wires 42 and 36 to battery 27. 65

If the motor M' should stall for any reason while moving the switch, an excessive current will traverse the motor circuit, but such excessive current will heat the thermostatic wire X to such a degree as to expand the same sufficiently to cause arm A to trip the circuit breaker. Contact F G now being opened, the circuit for the motor M' is of necessity disrupted, thus preventing 70 injury to the motor or to other apparatus in 75 the motor circuit.

Should the stalling of the motor M' be caused by some obstruction between the switch rails and track rails, it is obvious that after the wire X has cooled sufficiently, 80 the pole-changer 11 may be shifted, thus resetting the circuit breaker and thereby causing the motor M' to return the switch operating mechanism to its original position ready to make another attempt to crush the 85 obstruction.

Although I have herein shown and described only one form of circuit breaker and one form of apparatus employing such circuit breaker embodying my invention, it is 90 understood that various changes and modifications may be made therein within the scope of the appended claims without departing from the spirit and scope of my invention. 95

Having thus described my invention, what I claim is:

1. A circuit breaker comprising a contact biased to open position, a latch for moving said contact to and holding it in closed position, a thermostat for releasing said latch from said contact to allow the contact to open, and means for reciprocating said latch to open and close the contact and to return the contact to closed position after the latter has been opened by operation of the thermostat. 100

2. A circuit breaker comprising a contact biased to open position, a latch co-operating therewith, means for reciprocating said latch to open and close said contact, and a thermostat for releasing said latch from said contact. 105

In testimony whereof I affix my signature in presence of two witnesses.

WILLIAM H. McCLELLAND, Jr.
